INVENTOR.

Henry C. Tallman

UNITED STATES PATENT OFFICE.

HENRY C. TALLMAN, OF CRANSTON, ASSIGNOR TO CHARLES F. IRONS, OF PROVIDENCE, RHODE ISLAND.

MOLD FOR INGOTS.

SPECIFICATION forming part of Letters Patent No. 412,566, dated October 8, 1889.

Application filed May 31, 1889. Serial No. 312,798. (No model.)

To all whom it may concern:

Be it known that I, HENRY C. TALLMAN, of the town of Cranston, in the county of Providence, in the State of Rhode Island, have invented a certain new and useful Improvement in Ingot-Molds; and I declare the following to be a specification thereof, reference being had to the accompanying drawings.

Like letters indicate like parts.

10 Figure 1 is a side elevation of my invention, with the mold shown partially in section on the line $x-x$ of Fig. 2. Fig. 2 is a top plan of said invention.

15 My invention relates to the metallic molds used in casting ingots, more especially of gold; and it consists of a solid mold having a central and tapering matrix, an indentation at its top on one side for the crucible to rest in, and a hub integral with said mold, in which 20 hub a handle may be secured, as hereinafter specified.

25 In the drawings, A represents a solid mold made, preferably, of cast-iron, having a central and slightly-tapering matrix a . On the front top edge thereof is an indentation or recess b , and on the opposite side is a hub c , cast integral with said mold. The hub c may be centrally bored and screw-threaded, as indicated in dotted lines in Fig. 1, and a handle 30 B , having a screw-threaded end, may be inserted in said hub, as shown. The check-nut d serves to prevent the handle from turning out of position.

35 Molds for casting gold and other ingots have hitherto been made as follows: Two pieces of steel, each having a central longitudinal channel planed therein. A series of holes is bored through these pieces on each side of the channel. The two pieces are then 40 placed with their channeled faces together, and a series of rivets is passed through said holes from side to side, and they are headed by hammering in the usual manner. A plug is driven into the channel or opening thus 45 formed and closes one end of the mold. The handle has usually been attached to the mold by a metallic loop, which, extending from the handle, passes around the mold on the outside and is secured thereto by a set-screw or 50 otherwise.

Great inconvenience and much difficulty have been experienced in the use of ingot-molds thus constructed. The repeated heating of a mold so made causes the gradual expansion and consequent lengthening of the 55 rivets by which the two pieces are held together, so that these two halves or pieces of the mold are not kept in perfect contact, but are slightly separated. The melted gold, when poured into the matrix, flows into the 60 cracks or openings thus formed. When the gold cools and solidifies, the ingot cannot be easily taken out, because it is held by the slight ribs on two of its opposite sides, which have been thus formed within the cracks or 65 openings between the two parts of the mold. Besides this, the grooves or tool-marks left all along the surface of the matrix by the planing operation above mentioned when the channels are made still further tend to 70 hold the ingot frictionally in the mold and prevent its easy removal. It is often, therefore, necessary in the use of a mold of this description to dislodge the ingot by turning the mold upside down and striking heavy 75 blows with it, or sometimes to remove the plug at the bottom of the matrix and force the ingot out by pounding a rod or bar against the inner end of the ingot.

It is the purpose of my invention to avoid 80 these difficulties. As my improved mold is made in one piece cast solid on all sides, with a central matrix formed by casting around a core instead of by riveting together channeled pieces, there are no parts to separate and no 85 harmful expansion or contraction is possible.

In casting my mold I use a smooth steel core, so that the surfaces of the matrix are left smooth and are wholly free from grooves, tool-marks, projections, or roughness of any 90 kind. The result is that when the melted gold has cooled in the mold and has become solidified the ingot drops easily out of the mold without any hindrance when the mold is inverted, and repeated use does not impair 95 the usefulness of the mold in this respect. The indentation or notch b is useful to receive the corner or edge of the crucible and to prevent the sidewise displacement of the latter while the molten metal is poured there- 100

from. As the crucible must be handled with tongs on account of its great heat, it is often difficult to keep it steadily in the required place while emptying and it is liable to slip 5 to an improper position. Such an indentation may as well be employed for the same purpose in ingot-molds of the common construction.

Instead of having the handle B separable 10 and connected with screw-threads to the hub of the mold, it may, if desired, be cast in one piece with the mold.

An ingot-mold made as specified herein is 15 much cheaper in cost as well as more durable and more easily used.

I claim as a useful and novel invention and desire to secure by Letters Patent—

1. The combination of the mold A, having the matrix a, the hub c, the handle B, screwed into said hub, and the check-nut d, substantially as specified.

2. The improved ingot-mold A herein described, having the matrix a, the crucible-notch b, the hub c, the handle B, screwed into said hub, and the check-nut d, substantially 25 as shown.

HENRY C. TALLMAN.
